UNITED STATES PATENT OFFICE.

JAMES A. WOTTON, OF CRANFORD, NEW JERSEY, ASSIGNOR TO WESTERN ELECTRIC COMPANY, OF NEW YORK, N. Y., A CORPORATION OF ILLINOIS.

SELECTIVE SIGNALING DEVICE.

1,124,680.

Specification of Letters Patent. Patented Jan. 12, 1915.

Application filed August 31, 1911. Serial No. 647,080.

To all whom it may concern:

Be it known that I, JAMES A. WOTTON, a citizen of the United States, residing at Cranford, in the county of Union and State 5 of New Jersey, have invented a certain new and useful Improvement in Selective Signaling Devices, of which the following is a full, clear, concise, and exact description.

This invention relates to selective signaling devices of that class comprising a quick and a slow acting magnet adapted to receive current in series, a movable contact-making device, and stepping and holding pawls controlled by said quick and slow-acting magnets for causing the advance of said movable contact-making device.

The invention relates more particularly to a selective signaling device of this class for use in a system wherein selection is made 20 by advancing all of the selectors simultaneously until certain ones comprising a group have closed contacts individual to each selector which causes the release of the 25 selectors of that group and again advancing all of the selectors until the particular one of a released group closes a signaling contact.

The object of the invention is to provide a simple and efficient combination of contacts 30 on the selector for accomplishing this purpose, and consists specifically in providing two contact arms of different lengths preferably secured to a ratchet wheel and locating adjacent to the ratchet wheel and in the 35 path of the movement of said contact arms two spring contact members, one of which co-operates with either of said arms to close a releasing circuit for the selector, the other of which is brought into operation 40 only in conjunction with the longer of said arms and closes a signaling circuit.

In the drawings illustrating this invention—Figure 1 is a front elevation of the selector with parts broken away; Fig. 2 is a schematic of the selector illustrating the 45 position of the parts and circuits completed with one of the contacts closed; Fig. 3 is a schematic of the selector illustrating the position of the parts and the circuits completed 50 with the other of said contacts closed; Fig. 4 is a fragmentary detail view showing the arrangement of the selector contact springs.

In the drawings, 1 designates a base upon 55 which is mounted an inverted U-shaped

frame having side members 2, 2, a top member 3 and supporting lugs 4, 4.

Suspended from the top member 3 of the U-shaped frame are two electromagnets 5 and 6 each comprising two coils.

Pivottally supported near the lower end 60 of the U-shaped frame are armatures 14 and 15, the armature 14 being responsive to electromagnet 5 and armature 15 being responsive to electromagnet 6, said electromagnet 6 being made slow-acting, as more clearly indicated in Figs. 2 and 3. The armatures 14 and 15 are provided with arms 25 and 26 respectively which are brought out through openings in the frame and are 70 extended upwardly along the end of said frame.

Attached to the upwardly extending arm 25 is an arm 27 carrying at its upper end a pivotally mounted spring-pressed pawl 28 75 adapted in the movement of the armature 14 to engage the teeth of a ratchet wheel 29 carried in an auxiliary frame 30 mounted upon the U-shaped frame. A holding pawl 31 mounted upon the frame of the selector 80 is adapted to be drawn into engagement with the ratchet wheel 29 by the action of a spring 32.

Secured to the armature 15 are two angularly disposed arms 33 and 34, the arm 33 85 being normally in engagement with the pawl 28 and the arm 34 with the pawl 31. The energization of the magnet 6 withdraws said arms from engagement with the respective pawls, permitting said pawls to engage said 90 ratchet wheel to rotate it in one direction.

A coiled actuating spring 35 is provided for returning said ratchet wheel to normal position upon the withdrawal of the pawls therefrom. Springs 38 and 39 are adapted 95 to return the arms 27 and 34 to normal position when the corresponding magnet is de-energized.

Mounted upon a projecting lug 37 carried by the magnet frame are two flexible spring contact members 40 and 41. The member 40 is the shorter and is in mechanical engagement with the arm 27 through a laterally projecting arm 42 (see Fig. 4) on said spring which engages an insulating pin 43 100 carried by said arm 27. The tension of the spring 40 being in a direction to force it against the arm 27 said spring will partake of the movement of said arm during the operation of the magnet 5. The contact spring 105 110

41 which is mounted to the rear and in line with the spring 40 is provided with a projection 44 which normally bears against an insulating pin 45 on the outer end of the arm 27 when the selector parts are in their normal or inoperative position, and against an insulating button 46 on the outer end of the arm 33 of the holding magnet armature when the two armatures are in their attracted position.

Carried by the ratchet wheel 29 are two contact arms 50 and 51 adapted in the rotation of said ratchet wheel to be brought into engagement with the contact spring 40. 15 As shown in the drawings the contact arm 50 is shorter than the arm 51 and when this shorter arm is brought into engagement with the contact spring 40, as shown in Fig. 2, it pushes said contact spring away from engagement with the arm 27 and the contact made by engagement of said arm 50 with the spring 40 completes a short circuit of the magnet 6. This will cause the de- 20 energization of the magnet 6 and permit the armature 15 thereof to drop back to normal position. The contact spring 41 remains in engagement with the arm 33 until said spring is brought into engagement with the insulating pin 45 on the arm 27 whereupon 25 further forward movement of this spring is prevented. The insulating pin upon the arm 27 is of such length that with the contact arm 50 in engagement with the spring 40 and the holding magnet armature released there will be a slight separation between the springs 40 and 41. The contact of 30 spring 41 with spring 40 closes a signaling circuit and is brought about by the engagement of the contact arm 51 with the spring 40.

As shown in Fig. 3 the engagement of the arm 51 with the spring 40 will complete a short circuit of the holding magnet 6 as in the former case, but the arm 51 being longer 45 than the arm 50 the contact spring 40 will be held in a position beyond the outer end of the insulating pin 45 so that as the spring 41 follows the arm 33 forward upon the release of the armature 15 it will be brought 50 into contact with the spring 40 and a circuit will be completed for a signal 60.

In the equipment of a system with selectors embodying this invention the selectors will be arranged in groups, each group comprising, say for example, three selectors although any number within a reasonable limit may comprise a group. All of the selectors comprising one group will have their arms 50 arranged so that they will be brought into engagement with the corresponding contact springs in response to the same number of current impulses sent over the line but no two groups will have the parts 50 and 40 in contact at the same time. 60

65 The separate selectors of each group will be

so arranged that a different number of impulses will be required to bring the contact arm 51 into engagement with the spring 40 in the case of each selector. It will be noted, however, that one selector of each group 70 may be arranged to have its contacts 51 and 40 closed in response to the same number of impulses without causing confusion so long as no two groups are released by the same number of impulses.

75

The battery current for operating the selectors may be supplied to the line wires from a central or despatching station through the operation of any well-known form of impulse transmitting apparatus.

80

I claim:

1. In a selective switching device the combination with a movable circuit-closing member, of contact arms carried thereby, a contact spring adapted to be separately engaged by each of said arms, a second contact spring and means controlling the movement of said second contact spring into engagement with the first mentioned spring when said first mentioned spring is in engagement 90 with one of said contact arms.

85

2. In a selective switching device the combination with a movable circuit-closing member, of two contact arms of different lengths carried thereby, a contact spring 95 adapted to be separately engaged by said contact arms, and a second contact spring brought into engagement with the first mentioned spring only by the engagement of the longer of said arms with said first mentioned spring.

100

3. In a selective signaling device the combination with a movable circuit-closing member, of electromagnets controlling the movement of said circuit-closing member, contact arms carried by said circuit-closing member, a contact spring adapted to be separately engaged by said contact arms, a second contact spring, and means actuated by one of said electromagnets for controlling the engagement of the second contact spring with the first mentioned spring in such manner that such engagement takes place only when said first mentioned spring is engaged 110 by one of said contact arms.

105

4. In a selective signaling device the combination with movable circuit-closing arms, of stepping and holding magnets for controlling the movement of said arms in one direction, a contact spring adapted to be 120 separately engaged by said contact arms, a second contact spring, and means actuated by said holding magnet for controlling the engagement of the second contact spring with the first mentioned spring in such manner that such engagement takes place only when said first mentioned spring is engaged 125 by one of said contact arms.

125

5. In a selective signaling device the combination with a toothed wheel and stepping 130

and holding pawls therefor, of a lever arm carrying said stepping pawl, a quick-acting magnet for operating said lever arm, a second lever arm controlling the engagement of said pawls with said ratchet wheel, a slow-acting magnet for operating said second lever arm, contact arms of different lengths carried by said ratchet wheel, a contact spring, a second spring normally held out of engagement with the first mentioned spring, and means carried by said second mentioned lever arm for holding said second spring out of engagement with the first

mentioned spring when said first mentioned spring is engaged by the shorter of said arms and to permit the engagement of said springs when said first mentioned spring is engaged by the longer of said arms. 15

In witness whereof, I, hereunto subscribe my name this 30th day of August A. D. 20 1911.

JAMES A. WOTTON.
